Primary Examiner — Rachel A. Voorhies(74) *Attorney, Agent, or Firm* — William J. Clemens; Shumaker, Loop & Kendrick, LLP(57) **CLAIM**

The ornamental design for a display screen with graphical user interface, as shown and described.

DESCRIPTION

The FIGURE is a front view of a display screen with a graphical user interface showing our new design.

The broken lines in the FIGURE showing the display screen illustrate portions of the article and form no part of the claimed design.
